OTTO PETERMANN, OF GROTON, NEW YORK, ASSIGNOR TO CORONA TYPEWRITER COMPANY, INC., OF GROTON, NEW YORK, A CORPORATION OF NEW YORK.

SEGMENT-SHIFT FOR TYPEWRITING MACHINES.

1,387,939.

Specification of Letters Patent. Patented Aug. 16, 1921.

Application filed September 11, 1918. Serial No. 253,544.

To all whom it may concern:

Be it known that I, OTTO PETERMANN, a citizen of the United States, and a resident of Groton, county of Tompkins, and State 5 of New York, have invented certain new and useful Improvements in Segment-Shifts for Typewriting-Machines, of which the following is a specification.

The principal object of the invention is 10 to provide simple and efficient means whereby the type-bar segment may be vertically shifted with respect to the platen to permit the use of type-heads carrying a plurality of characters, the principal features of the 15 present invention having special reference to that type of segment shift in which the segment is held normally in its uppermost position and is manually pulled down to its middle-case and upper-case position, as 20 more fully hereinafter set forth.

In the drawing annexed,—

Figure 1 is a vertical sectional view showing the parts in the positions they occupy when the segment is in its uppermost position; 25

Fig. 2 is a plan view of the same, the frame parts being shown in horizontal section on the line II—II of Fig. 1;

Fig. 3 is a fragmentary sectional view 30 on the line III—III of Fig. 1;

Fig. 4 is a view similar to Fig. 1 showing the parts in the position they occupy when the segment is pulled down to its intermediate position; and

Fig. 5 is a view similar to Fig. 4 showing the parts in the position they occupy when the segment is in its lowermost position.

Referring to the drawing annexed by 40 reference-characters, the numeral 10 designates the segment-carrying plate, the segment being omitted from the drawing. This plate extends across the machine at the rear thereof and is vertically guided at 45 its upper edge by means of a forwardly-extending ear 11, formed at each end of the upper edge of the plate and notched at its outer edge for sliding engagement with a vertical guide 12 carried by the frame. 50 The upward movement of the segment-plate is restricted by a pair of depending stops 13 adapted to strike against the upper surfaces of the ears 11, these stops consisting in the present instance of adjustable screw-pins 14 threaded through the top of the

frame and locked in their adjusted position by means of lock-nuts 15.

Projecting forwardly from the lower part of the segment-carrying plate 10 adjacent opposite ends thereof are two ears 16, and 60 pivotedly connected to these ears is a pair of arms 17, one lying near each side of the frame and both being affixed rigidly to rock-shaft 18 journaled in the side members of the frame. Depending from the 65 rock-shaft is a rigid pin 19, and connected to the lower end of this pin is a coil-spring 20 whose rear end is attached to a screw 21 supported by the frame and adapted to be adjusted forwardly and rearwardly to 70 vary the tension of said spring. This arrangement of devices, as is obvious, tends to normally hold the segment-plate in its uppermost position, *i. e.*, lower-case position.

The segment is locked in its upper position by means of a lock-bail consisting of a bar 22 extending across the machine from side to side underneath the segment-shifting arms 17 and pivotally hung from the 80 front face of the segment by means of a pair of upstanding arms 23 connected to the ends of said bar 22, these arms 23 being pivotally connected to the segment by means of pivots 24 affixed to ears 25^a projecting forwardly 85 from the face of the segment-plate. Each of the arms 23 is provided with an extension which extends upwardly from its pivot 24, and these extensions 25 are normally pulled rearwardly by coil-springs 26 connecting the arms to the segment-plate. Normally pulling the extensions 25 rearwardly causes the bar 22 to normally wedge 90 against the top of an upstanding stop 27 mounted on the base-frame, the upper or 95 operative face of this stop being inclined downwardly and rearwardly to bring about the aforesaid wedging action with the lock-bail-bar 22.

It will be obvious that to move down the 100 segment to its intermediate or to its lower position, it is first necessary to throw the lock-bar 22 rearwardly off the stop 27. This is accomplished by a pair of key-levers 28 and 29 pivotally mounted at each side of 105 the machine, each pair of levers being supported on a pivot 30 and each lever being held in its normal position, *i. e.*, with its finger-key up, by means of a retractile-spring 31. Each pair of levers is adapted 110

when depressed to engage a lateral lug 32 formed on the adjacent one of the arms 17, so that the depression of any one of the shift-keys will bring about a downward-5 swinging of the forward ends of the arms 17 against the action of the spring 20 and thus pull down the segment.

The key-levers 28 and 29 are provided respectively with arms 28^a and 29^a which 10 extend upwardly and rearwardly and are provided each with a laterally-bent finger portion 34 which lies immediately behind the rear edge of the adjacent one of the arms 25. The arms 29^a are shorter than 15 the arms 28^a, so that when they are operated by either one of their keys they will swing the lock-bail 22 a greater distance rearwardly than the arms 28^a.

When either of the key-levers 28 is depressed, the lock-bail will be swung to the 20 position shown in Fig. 4 and at the same time the segment will be pulled down through the medium of the arms 17. In this position of the lock-bail 22, it will 25 strike squarely against a stop-pin 35 supported in one of the cross-bars of the frame and rendered vertically adjustable by being tapped therethrough, a lock-nut 36 being provided to lock this stop-pin 35 in its adjusted position. This movement of the parts 30 will bring the segment to its middle position and will arrest it quickly and accurately in that position; and when the operator releases the key the spring 20 will restore 35 the segment to its upper position, while the spring or springs 26 will automatically restore the lock-bail-bar 22 to locking relation with the stop 27. When either of the other keys 29 is depressed, the shorter arms 40 29^a will swing the lock-bail far enough rearwardly to escape the stop-pin 35 when the segment is pulled down through the medium of the arms 17, so that the lock-bail does not interfere with the movement downwardly of the segment. This downward movement of the segment, however, is arrested by another stop-pin 37 arranged in vertical alinement with the segment-plate 10 so that the lower edge of the segment- 45 plate will strike squarely on top of this pin 37 and thus arrest the segment in its lower position. The stop-pin 37 is made vertically adjustable and is locked in its adjusted position in the same manner as stop- 50 pin 35. It will be understood that one or more of these stop-pins may be employed for each segment-shift.

The nature and scope of the invention having been thus indicated and its preferred 60 embodiment having been specifically described, what is claimed as new is:

1. In a typewriting machine, the combination of a machine frame, a type-bar-hanger support, means for guiding the sup- 65 port to move up and down in the frame, a

rock shaft extending transversely of the frame and rotatably supported thereon forward of the type-bar-hanger support, a pair of rock arms rigidly held at their forward ends to said shaft and connected at their rear ends with the hanger support, one of 70 said rock arms being provided intermediate its ends with a lateral projection, a depending arm rigidly held to the rock shaft, a coil spring connected at its forward end with 75 said depending arm, tension adjusting means connecting the rear end of the spring with the frame, and a shift key lever overlying said projection on the rock arm and pivotally supported in the frame at a point at 80 the rear of said projection.

2. In a typewriting machine, the combination of a machine frame, a type-bar-segment support, means for guiding the support to move up and down in the frame, a 85 rock shaft journaled in the frame and extending transversely thereof, a pair of rock arms rigidly held to said shaft and connected with said support to raise and lower the support, each of said arms having a 90 lateral projection, a pair of shift key levers fulcrumed in the frame adjacent opposite sides of the frame and each overlying the projection on the adjacent rock arm intermediate its fulcrum and key-carrying end, 95 a spring for normally rocking the shaft and arms in a direction to elevate the support, and means releasable by the operation of either of said key levers for locking the segment support in its normal elevated position. 100

3. In a typewriting machine, the combination of a machine frame, a type-bar segment support, means for guiding the support to move up and down in the frame, 105 a rock shaft journaled in the frame and extending transversely thereof, a pair of rock arms rigidly held to said shaft and connected with said support to raise and lower the support, each of said arms having a 110 lateral projection, a pair of shift key levers fulcrumed in the frame adjacent opposite sides of the frame and each overlying the projection on the adjacent rock arm intermediate its fulcrum and key-carrying end, a 115 spring for normally rocking the shaft and arms in a direction to elevate the support, a fixed abutment on the frame, and spring urged latching means mounted on the segment support co-operating with said abutment to lock the support in its normal elevated position and releasable by either of the key levers. 120

4. In a typewriting machine, the combination of a machine frame, a type-bar segment support, means for guiding the support to move up and down in the frame, a 125 rock shaft journaled in the frame and extending transversely thereof, a pair of rock arms rigidly held to said shaft and connect- 130

- ed with said support to raise and lower the support, each of said arms having a lateral projection, a pair of shift key levers fulcrumed in the frame adjacent opposite sides 5 of the frame and each overlying the projection on the adjacent rock arm intermediate its fulcrum and key-carrying end, a spring for normally rocking the shaft and arms in a direction to elevate the support, a bail 10 having a bar extending transversely of the machine and upstanding arms pivotally held to the segment support, a fixed abutment on the frame, a spring for forcing the transverse bar of the bail over said abutment 15 to lock the support in its normal elevated position, and an arm on each key lever for rocking the bail out of engagement with said abutment.
5. In a typewriting machine, the combination of a machine frame, a type-bar segment support, means for guiding the support to move upon and down in the frame, a rock shaft journaled in the frame and extending transversely thereof, a pair of rock 20 arms rigidly held to said shaft and connected with said support to raise and lower the support, each of said arms having a lateral projection, a pair of shift key levers fulcrumed in the frame adjacent opposite sides 25 of the frame and each overlying the projection on the adjacent rock arm intermediate its fulcrum and key-carrying end, a spring for normally rocking the shaft and arms in a direction to elevate the support, 30 means on the segment support and frame having coacting cam faces for locking the segment in its elevated position, and an arm on each key lever loosely engaging the locking means on the segment support for releasing the support when either key lever is 35 operated.
6. In a typewriting machine of the class in which the type-bar-support is normally held up and is manually depressed by case-shift key-levers, two stops on the base one of 40 these stops being in direct alignment with the support, a swinging stop-member carried by the support and adapted to coöperate with the other stop, and devices operated from said key-levers to select the desired 45 stop.
7. In a typewriting machine, the combination of a support shiftable different distances to vary the relation between printing 50 instrumentalities and a platen, spring means for moving said support to its normal position, a pair of key-operated levers for shifting the support in opposition to said spring, and means shiftably mounted on the support 55 and movable a different distance by each lever for determining the case-shift positions to which the support is movable by the levers.
8. Double case shift mechanism for typewriting machines comprising a support shift- 60
- able to vary the relation between printing instrumentalities and a platen, fixed means coöperating with the support for determining the maximum limits of movement of the support, a stationary intermediate stop, 70 a stationary locking abutment, a member shiftably mounted on the support normally engaging said locking abutment to hold the support at one limit of its movement, and a pair of key-operated levers operatively 75 connected with the support for shifting the same, one of said levers being connected with the shiftable member on the support to release the same from the locking abutment and hold it in a position to engage the 80 intermediate stop and the other lever being connected with said member to shift the same out of engagement with the abutment to a position in which it will pass the intermediate stop.
9. In a typewriting machine of the class in which the type-bar-segment is normally held up and is manually depressed by case-shift key-levers, two stops for arresting the 85 segment at different levels, and means controlled from the said key-levers to select the desired stop, said means embodying a swinging bail carried by the segment and adapted to coöperate with one of said stops, and a lock-stop adapted to coöperate with said bail 90 when the segment is up to lock the segment in its upper position.
10. In a typewriting machine of the class in which the type-bar-segment is normally held up and is manually depressed by case-shift key-levers, two stops for arresting the 95 segment at different levels, means controlled from the said key-levers to select the desired stop, said means embodying a swinging bail carried by the segment and adapted to coöperate with one of said stops, and a lock-stop adapted to coöperate with said bail 100 when the segment is up to lock the segment in its upper position, said bail and said lock-stop being constructed to have a wedging or 105 camming action.
11. In a typewriting machine, the combination of a frame, a support shiftable up and down in the frame to change case, means carried on the frame for determining the 110 uppermost and lowermost positions of the support, a spring normally forcing the support to its uppermost position, a locking and shift-controlling member pivotally held to the support, a spring for normally swinging 115 said member into engagement with a stationary part of the machine to lock the support in its normal uppermost position, a stationary stop for arresting the support in an intermediate position, and a pair of shift 120 keys operatively connected with the support for shifting the same downwardly and operatively connected with said member for swinging the same different distances, said member being adapted to engage the inter- 125
- 65 130

- mediate stop when shifted by one of said keys.
12. In a typewriting machine, the combination of a support shiftable to vary the relation between printing instrumentalities and a platen, a spring for normally shifting the support upwardly, a locking and shift-controlling device shiftably held to the support, key-operated means for shifting the support downwardly against the action of said spring, three stepped stops one of which is adapted to be engaged by the support to arrest the support in its lowermost position and the other two of which are adapted to be engaged by said device to respectively lock the support in its uppermost position and arrest the support in an intermediate position, said device being controlled by said key-operated means.
13. In a typewriting machine, the combination of a support shiftable different distances to vary the relation between printing instrumentalities and a platen, yieldable means for moving the support to a normal elevated position, a pair of key-operated levers operatively connected with the support for shifting the same downward, a pair of stationary stops one of which is adapted to be engaged by the support to arrest the support in its lowermost position, and a bail pivotally held to the support to swing fore and aft of the machine and shiftable by one of said levers into position to engage the other stationary stop when the support is moved downward by said lever.
14. In a typewriting machine, the combination of a support shiftable different distances to vary the relation between printing instrumentalities and a platen, yieldable means for normally moving the support upward, means coöperating with the support for determining the uppermost and lowermost positions of the support, a pair of stepped abutments spaced fore and aft of the machine, a bail having its side arms pivotally held to the support to swing fore and aft of the machine, a spring normally swinging the bail in one direction to engage the transverse portion thereof over the higher abutment and lock the support in its normal uppermost position, a pair of key-levers having key-carrying arms and arms connected with a side arm of the bail different distances from the pivotal point of the bail arm, and connections between the key-levers and support for lowering the support.
15. In a typewriting machine, the combination of a support shiftable different distances to vary the relation between printing instrumentalities and a platen, yieldable means for normally moving the support upward, means coöperating with the support for determining the uppermost and lowermost positions of the support, a pair of stepped abutments spaced fore and aft of

the machine, a bail having its side arms pivotally held to the support to swing fore and aft of the machine, a spring normally swinging the bail in one direction to engage the transverse portion thereof over the higher abutment and lock the support in its normal uppermost position, a pair of key-levers having key-carrying arms loosely engaging the support moving means for lowering the support and arms loosely engaging one of the side arms of the bail different distances from the pivotal point of the bail arm for swinging the bail different distances in opposition to the spring.

16. In a typewriting machine, the combination of a frame, a type-bar-hanger support, a pair of short vertical guides at opposite sides of the upper part of the frame, said support having slotted portions adjacent its upper edge at opposite sides thereof embracing said guides, a rock shaft journaled in the frame and extending transversely thereof, a pair of rock arms extending fore and aft of the frame rigidly held at one end to said shaft and pivotally connected at their other ends with the support adjacent the lower edge of the support, a spring for normally rocking said arms upwardly and key-operated means for rocking said arms downwardly.

17. In a typewriting machine, the combination of a frame, a type-bar-hanger support, a pair of short vertical guides at opposite sides of the upper part of the frame, said support having slotted portions adjacent its upper edge at opposite sides thereof embracing said guides, a rock shaft journaled in the frame and extending transversely thereof, a pair of rock arms extending fore and aft of the frame rigidly held at one end to said shaft and pivotally connected at their other ends with the support adjacent the lower edge of the support, a spring for normally rocking said arms upwardly, a pivoted latch mounted on the support for locking the support in its normal elevated position, and a key lever having an arm connected with one of the rock arms for rocking the arms downwardly and an arm connected with said latch for releasing the support when the key lever is actuated.

18. Multiple case shift mechanism for typewriting machines comprising a support shiftable different distances in one direction from a normal position to vary the relation between printing instrumentalities and a platen, a plurality of shift keys connected to shift said support, and a swinging locking and shift-control member for automatically locking the support in normal position shiftable different distances from its locking position by said keys to determine the case-shift position to which the support will be moved by each key.

19. Multiple case shift mechanism for

- typewriting machines comprising a support shiftable different distances in one direction from a normal position to vary the relation between printing instrumentalities and a platen, a plurality of shift keys connected with the support for shifting the same, a locking and shift-controlling member movably mounted on the support and adapted to engage a stationary part of the machine to 5 lock the support in normal position, said member being shiftable from locking position a different distance by each key to determine the case-shift position to which the support is movable by the key.
- 15 20. Double case shift mechanism for typewriting machines comprising a support shiftable from a normal position to two other positions to vary the relation between printing instrumentalities and a platen, a pair of 20 shift key levers connected to shift the support having key-carrying arms and shift-controlling arms, and a swinging member adapted to lock the support in its normal position, said shift-controlling arms on the 25 key levers engaging said member different distances from its pivotal axis for swinging the member different distances to determine the case-shift positions to which the support is movable by the key-levers.
- 30 21. Double case shift mechanism for typewriting machines comprising a support shiftable from a normal position to two different positions to vary the relation between printing instrumentalities and a platen, a swinging 35 locking and shift-controlling member, a spring for normally moving said member to a position to lock the support in normal position, a pair of key levers having key-carrying arms connected with the support to shift 40 the support and arms of different length extending at an angle to the key-carrying arms and loosely engaging the swinging member for moving said member different distances to determine the case-shift positions to which 45 the support is movable by the key levers.
22. In a typewriting machine, the combination of a frame, a support shiftable vertically different distances in the frame to vary the relation between printing instrumentalities and a platen, a rock shaft journaled in the frame and extending transversely thereof, a rock arm fixed on said shaft and pivotally connected with the support and having a lateral projection intermediate the shaft and support, a spring for 50 normally rocking the arm upward to elevate the support, a swinging support-locking and shift-controlling member adapted to lock the support in its normal elevated position, and a pair of shift levers having parts loosely 55 engaging over the projection on the rock arm to rock the arm downward, each of said levers being also provided with a part loosely engaging said member and adapted to shift the same from locking position to a 60 position determining the case-shift position to which the support is movable by the lever.
23. Double case shift mechanism for typewriting machines comprising a support shiftable different distances in one direction from a normal position to change case, fixed means coöperating with the support to determine the maximum limits of movement of the support, a stationary intermediate stop, a stationary locking abutment, a member pivotally held to the support normally engaging the abutment to lock the support at one limit of its movement, a spring normally swinging said member to locking position, and a 65 pair of shift keys operatively connected with the support for shifting the same, one of said keys being connected with said member to swing the same from locking position into coöperative relation with the intermediate 70 stop and the other key being connected with said member to swing the same out of locking position to a position out of coöperative relation with the intermediate stop.
- This specification signed this fifth day of 75 September, A. D. 1918.
- OTTO PETERMANN.
